RECEPTACLE FOR PAPER SHEETS

Charles A. MacCordy, Fulton, N. Y.

Application May 10, 1944, Serial No. 534,971

8 Claims. (Cl. 312—50)

1

The invention relates to improvements in paper sheet dispensers and, more particularly, to improvements in dispensers designed for direct manual withdrawal of sheets one at a time from a pack or supply of loose sheets housed within the dispenser.

The general purpose of the invention is to provide an improved paper sheet dispenser which is so constructed that it can readily be loaded with a pack or supply of loose or disconnected paper sheets such, for example, as blank sheets or as printed money order blanks, time slip blanks, etc. without creasing or interfolding of the sheets, that it will prevent scattering and soiling and waste of the supply of sheets, and that sheets may readily be directly withdrawn by hand one at a time from the dispenser.

A more specific purpose of the invention is to provide a sheet dispenser which will maintain a pack of loose sheets therein in a bowed condition and which has an end wall slotted for insertion therethrough of a human finger to withdraw the bowed sheets bowed end first one at a time out through said slot, the inner face of said slotted end wall being shaped to contract the leading end of the bowed sheet engaged by the finger until said end of the sheet is bowed sufficiently to pass through the slot.

A further detail feature of the invention comprises provision of a pack positioner within the dispenser in line with one end of the slot in the slotted end wall of the dispenser to prevent a pack of sheets from rotating in the dispenser into a position in which the pack extends entirely across the slot at both ends of the slot.

Further detail features included within the scope of the invention consist in provision whereby the supply of sheets may be inserted in the dispenser either through the finger slot or through the opposite end of the dispenser, and in provision for fixedly securing the dispenser to a table, shelf, bracket or other support.

Other features and advantages will appear from the following description of two illustrative embodiments of the invention shown in the drawings.

In the drawing:

Figure 1 is a top plan view of one form of sheet dispenser embodying the invention;

Figure 2 is a sectional view on the line 2—2 of Figure 1;

Figure 3 is a perspective view (with parts broken away) of the dispenser disclosed in Figures 1 and 2, showing the last sheet of a pack being withdrawn from the dispenser.

2

Figure 4 is a sectional view on the line 4—4 of Figure 5 showing a modified form of the dispenser; and

Figure 5 is a sectional view of the modified form of dispenser taken on the line 5—5 of Figure 4.

The dispenser shown in Figures 1 to 3 includes a pack housing or casing constructed to provide a pack receiving chamber shaped to hold a pack 10 of loose paper sheets in arcuately bowed condition. This casing, in the construction shown, has a cylindrical wall 11 and two opposed end walls 12 and 13. The end wall 12 is provided with a diametrically extending slot 14 the end edges of 15 which are coincident with the inner surface of the cylindrical wall 11. It will be obvious that the outer surface of wall 11 need not necessarily be cylindrical.

The inner face of end wall 12 lies in two planes 20 of equal and opposite inclination to form two sloping planar cam surfaces 15 which extend from the respective longitudinal edges of slot 14 to the inner face of the cylindrical wall 11. The outer face of wall 12, in the construction shown, 25 is a planar face and is normal to the axial line of the cylindrical wall 11 but it may have a rounded or other contour.

The other end wall 13 preferably has planar 30 inner and outer faces normal to the axial line of the cylindrical wall, and, preferably, is provided with a small central countersunk hole 16 through which may be passed the shank of a screw, nail or other fastener to attach the dispenser to a suitable support, such as a wall, table, shelf or 35 the like. Preferably, as shown, the walls 11 and 12 are formed integrally, and the wall 13 formed as a separate flat disk seated in a counterbore 17 formed in the adjacent end of the cylindrical wall 11.

Within the casing there is provided a pack-locating bar or fin 18 which extends, in the direction of length of said bar or fin and in the direction of the length of the axial line of wall 11, along and against the inner face of the wall 11, opposite one end of slot 14. This bar or fin 18, in the construction shown, is rigidly affixed at one end thereof to end wall 13, as by cementing or welding it to said wall, but it may be formed integrally with said wall if desired.

The separable parts or sections of the dispenser shown are held in assembled relation by a fastening device 19 which is engaged with wall 11 and the bar or fin 18. As shown, this fastening device is a screw passed radially through wall 11 and 55 having threaded engagement in the bar or fin 18.

but it may be a nail, a drive screw, or other fastener not conveniently removable. If desired, the fastener may be a quickly removable cotter or the like.

In the construction shown in Figures 1 to 3, access to the interior of the dispenser can quickly and conveniently be had solely through slot 14, and a pack of sheets to be dispensed is therefore placed in the dispenser through this slot. To load this dispenser, the pack of loose sheets is sharply flexed or bowed to assume a U-form in end elevation, and is then passed inward through the slot and released so that the pack finally expands into a generally arcuate form in end elevation, such expansion being limited by the cylindrical wall 11. The pack is so inserted that the fin or locator bar 18 is interposed between the separated edges of the bowed pack. The locator bar or fin 18 is so located opposite one end of slot 14 to prevent the pack from extending fully across slot 14 at opposite sides of the axial line of the cylindrical wall. The bar 18 should extend far enough from wall 11 toward the axial line of wall 11 to block rotation of any and all sheets of a pack of the thickness conveniently insertible in the dispenser to an extent which would permit the pack, or any sheet thereof, to extend fully across slot 14 at opposite sides of the axial line of wall 11. For this purpose, the bar or fin 18 may extend, for example, to said axial line or even across said axial line. However, a bar extending to the extent shown toward said axial line will block such excessive and improper rotation of any pack, or of any sheet or sheets thereof, such as would ordinarily be loaded in the dispenser.

The locator bar or fin 18 may be of truncated wedge form in cross section as shown and, where it is desired or necessary to load the dispenser through the slot 14, the bar is preferably tapered as shown at 18a-18b to a rounded free end edge 18a from a point intermediate the free end of the bar and the wall 13.

In Figure 1 there is indicated generally at 20 a pack of loose sheets which has been inserted through slot 14 and released, it being understood, of course, that the thickness of the sheets is greatly exaggerated in the drawing over that of sheets which would usually be employed, and it will also be understood that the entire pack or any sheet or sheets thereof may assume a different position about the axial line of the cylindrical wall as far as such change of position over that shown is permitted by the locator bar or fin 18.

The longitudinal side edges or edge walls of slot 14 are preferably straight and parallel, as shown. The slot should be wide enough to permit the index finger of any normal person to be freely inserted through the slot. In the construction shown, which is drawn to scale from a sample dispenser for small sheets, this slot is one inch wide and this width will easily accommodate any normal index finger and permit a substantial number of bowed sheets to be inserted into the dispenser at one time through the slot without creasing the sheets. Obviously, the slot may be made wider than one inch, and it may be made somewhat narrower than one inch, but must be wide enough for convenient insertion of a finger through the slot.

To withdraw a sheet from a pack housed in the dispenser, a person inserts a finger (usually and naturally an index finger) through the slot, presses the finger to the innermost sheet of the pack and withdraws the finger through the slot while maintaining pressure on the sheet. As the

finger is withdrawn, the finger-contacted sheet is pulled toward the wall 12 and the leading end of the sheet engages both of the cam surfaces 15 which then progressively increase the bowing of the sheet at said end until said end is bowed sufficiently, without creasing the sheet, to pass through slot 14. After the leading bowed, but uncreased, end of the sheet being withdrawn from the dispenser has passed through the slot, it naturally tends to flatten out, and the person withdrawing the sheet may grip the exposed portion of the sheet between the index finger and thumb for completion of the withdrawal of the sheet from the dispenser. In Figure 3 a sheet 20a is shown partially withdrawn from the dispenser. In order to permit the convenient withdrawal of the last sheet of the pack, the end of the slot opposite the fin 18 must coincide with the inner wall of the cylindrical wall 11.

In loading the dispenser through the slot 14, the entire pack of loose sheets to be loaded, or any desired portion thereof, is flexed into a sharp U-form, pushed through the slot, and then released, whereupon the charged or loaded sheets will expand into a curvilinear bowed form generally concentric with the cylindrical wall 11. In inserting the sharply bowed pack of sheets, the pack is passed through the slot so that the spaced edges of the pack will pass inward at opposite sides of the locator bar. It will be obvious that a pack may be inserted in the dispenser in installations.

The dispenser may be made of any suitable substantially rigid material, such as wood, metal, molded plastic material, etc. While the slotted end wall 12 has been shown formed integrally with the cylindrical wall, it will be obvious that these walls may be separately formed and suitably connected detachably or permanently.

The modified form of the dispenser illustrated in Figures 4 and 5 will now be described. This form of dispenser is constructed and is usable in the same manner, except as hereinafter described, as is the dispenser shown in Figures 1 to 3 and above described.

The modified form of dispenser has a cylindrical wall 11 with counterbore 17 in which is seated the flat disk-like end wall 13 to which the pack locator bar 18 is rigidly held, all as constructed and arranged in the dispenser shown in Figures 1 to 3 and above described.

In the modified construction, however, the end wall 13 and the connected bar or fin 18 are quickly and easily removable or detachable as a unit from the cylindrical wall 11. For this purpose, the wall 11 and the locator or pack-rotation-limiting bar or fin 18 are provided respectively with passages 21 and 22, which are registerable and are preferably generally cylindrical. The fastener substituted in this form of dispenser for the screw or the like 19 may be of any known construction permitting quick and easy removal of the fastener for ready separation of head or wall 13 and part 18 from the cylindrical wall 11. In the construction shown, this fastener comprises a cotter having a head 23 from which extend two spaced resilient legs 24, one of which legs is formed with a latching lug 24a at its inner end. After pushing the legs of this cotter through registering passages 21 and 22, the resilient legs spring apart and assume the condition shown, wherein the projection or lug 24a engages the inner edge of bar 18 to prevent accidental withdrawal of the cot-

ter but to permit, as hereinafter explained, ready withdrawal of the cotter when desired.

Also in the modified construction, the end wall opposed to end wall 13 is so modified as to provide an end wall 25 of uniform thickness, which wall is a segment of a hollow sphere and so merges with wall 11 that the respective centers about which the inner and outer spheroidal faces of said wall 25 curve are located along the axial line of said wall 11 and that the inner faces of walls 11 and 25 intersect in a plane normal to the axial line of wall 11, and the outer faces of said walls intersect in a plane normal to said axial line. The wall 25 is provided with a diametrical slot 26, with respect to which slot the apertures 21 and 22 are so located that member 18 bears the same relation to slot 26 in the modified dispenser that member 18 does to slot 14 in the construction shown in Figures 1 to 3. The ends of slot 26 at the inner face of wall 25 are coincident with the inner face of wall 11, and the width and use of this slot correspond to those of slot 14.

By in the modified construction, passing any rigid instrument, such as a screw driver, through slot 26 against lug 24a, the cotter legs may be relatively contracted to permit ready withdrawal of the cotter and subsequent detachment of wall 13 and member 18 from the remaining portions of the dispenser. When said wall 13 and member 18 are so detached, a pack of loose sheets to be dispensed may be charged or loaded into the dispenser through that end of the dispenser which is normally closed by wall 13.

In the two constructions of dispenser shown, it will be obvious that, if desired, the two spaced portions of the inner face of wall 12 or of wall 25 may be merged with wall 11 by short concave junction surface portions in the nature of fillets. This will avoid relatively abrupt lines of intersection of the inner surface of wall 11 with the inner surface of the slotted end wall of the dispenser.

The primary difference between the sheet-bowing cam surfaces provided by the inner faces of slotted walls 12 and 25 at opposite sides of the slot is that in the construction shown in Figures 1 to 3 the cam surfaces are planar surfaces, whereas in the construction shown in Figures 4 and 5, the cam surfaces are spheroidal surfaces. In both instances the cam surfaces slope or converge toward the longitudinal edges of the diametrical slot in the slotted end wall.

It will be obvious that the dimensions of the dispenser must be proportioned to the size of the sheets to be dispensed, although, of course, a given dispenser will be adapted for use with sheets varying somewhat in size. The minimum internal dimension of the wall 11 measured from the inner face of wall 13 to either of the cam faces should not be less than one dimension of the sheet, which we will call the width. The other dimension or length of the sheet is limited by the length of the slot, as the slot must be at least about one-half the length of the sheet in order to permit the withdrawal of the sheet doubled as described. The end of the slot opposite fin 18 must extend to the inner surface of the wall 11 in order to permit withdrawal of the last sheet or sheets of a pack housed in the dispenser without obstruction by the slotted end wall. It is desirable that the slot extend at both its ends to the inner surface of wall 11, since such a full-length slot will accommodate a doubled sheet the length of which can readily be ac-

commodated around the internal circumference of the cylindrical wall 11. This is not essential, however, and the slot may extend from the surface of wall 11 opposite fin 18 only part way across the dispenser toward fin 18. In this latter case, it will be understood that the longest sheet which, when doubled, can be accommodated by the slot will occupy only a fraction of the circumference of wall 11 which could be used with a slot the full length of the internal diameter of the dispenser and a correspondingly longer sheet.

I claim:

1. A paper sheet dispenser which, to confine a pack of disconnected and superimposed paper sheets with the pack bowed about an axial line and to provide for manual withdrawal of sheets from the dispenser in one direction longitudinally of said axial line and sheet by sheet from the innermost to the outermost one of the bent and confined pack of sheets, comprises a housing having two end walls and a longitudinal wall connecting said end walls and forming therewith in the housing a pack confining chamber which has a cylindrical form from a closed end of said housing substantially to an opposite sheet withdrawal end of the housing to confine a pack of disconnected and superimposed paper sheets in said chamber with the pack of sheets bowed around the axial line of said chamber, said sheet withdrawal end of said housing having therein a diametrical slot extending entirely thereacross to provide a sheet withdrawal passage through said housing end, said chamber in the housing being progressively contracted adjacent the sheet withdrawal end of the housing toward the longitudinal edges of said slot to provide two spaced sheet-bowing cam surfaces within the chamber at opposite sides of the slot, said slot being wide enough for insertion of a human finger therethrough to frictionally draw one sheet at a time edgewise against said cam surfaces and out through the slot from a pack of sheets confined in said chamber and bowed about the axial line of the chamber, and rigid pack locating means held to the housing and extending inwardly from the longitudinal wall of the housing into said chamber toward the axial line of the chamber in registry with said slot for protrusion of said means between the adjacent edges of a bowed pack of sheets confined in said chamber with the pack bowed about the axial line of the chamber.
2. A paper sheet dispenser, as claimed in claim 1, wherein the chamber is contracted adjacent the sheet withdrawal end of said housing to provide within the housing two sheet-bowing planar cam surfaces of equal and opposite inclination which converge from the inner face of the longitudinal wall of the housing to opposite ones of the longitudinal edges of the sheet withdrawal slot.
3. A paper sheet dispenser, as claimed in claim 1, wherein the slotted sheet withdrawal end of the housing comprises one of the housing end walls which has the form of a segment of a hollow sphere the center of which is located within the pack-confining chamber and on the axial line of the pack-confining chamber, the inner spheroidal face of which end wall extends to the adjacent end of the cylindrical portion of the chamber.
4. A paper sheet dispenser which, to confine a pack of disconnected and superimposed paper sheets with the pack bowed about an axial line and to provide for manual withdrawal of sheets

in one direction longitudinally of said axial line and sheet by sheet from the innermost to the outermost one of the bent pack of sheets, comprises a housing having a pack-confining chamber defined by a cylindrical wall and by two end walls to confine a pack of such sheets with the pack bowed about the axial line of the cylindrical wall and to restrain movement of the pack longitudinally of said axial line, one of said end walls being provided with a diametrical sheet-withdrawal slot extending entirely thereacross and wide enough for insertion of a human finger therethrough for frictional face contact with the innermost one of a pack of sheets so confined in the chamber to withdraw the contacted sheet through said slot, said slot extending only to the juncture of the cylindrical wall with said slotted end wall, and the inner face of said slotted end wall being sloped from said cylindrical wall toward the respective longitudinal edges of said slot, and a fin-like pack locator held in the chamber to project part way across the chamber from said cylindrical wall substantially diametrically of the chamber and in registry with said slot, which locator is of less width than said slot at the end of said locator which is nearest said slot.

5. A paper sheet dispenser which, to confine a pack of disconnected and superimposed paper sheets with the pack bowed about an axial line and to provide for manual withdrawal of sheets in one direction longitudinally of said axial line and sheet by sheet from the innermost to the outermost one of the bent pack of sheets, comprises a housing having a pack-confining chamber defined by a cylindrical wall and by two end walls to confine a pack of such sheets with the pack bowed about the axial line of the cylindrical wall and to restrain movement of the pack longitudinally of said axial line, one of said end walls being provided with a diametrical sheet-withdrawal slot wide enough for insertion of a human finger therethrough for frictional face contact with the innermost one of a pack of sheets so confined in the chamber to withdraw the contacted sheet through said slot, one end of said slot being coincident with the juncture of the cylindrical wall with said slotted end wall, and the inner face of said slotted end wall being sloped from said cylindrical wall toward the respective longitudinal edges of said slot, and a fin-like pack locator held in and extending longitudinally of the chamber to project part way across the chamber from said cylindrical wall substantially diametrically of the chamber in registry with said slot and toward said one end of the slot.

6. A paper sheet dispenser which, to confine a pack of disconnected and superimposed paper sheets with the pack bowed about an axial line and to provide for manual withdrawal of sheets in one direction longitudinally of said axis and sheet by sheet from the innermost to the outermost one of the bent pack of sheets, comprises a housing having a pack-confining chamber defined by a cylindrical wall and by two end walls to confine a pack of such sheets with the pack bowed about the axial line of the cylindrical wall and to restrain movement of the pack longitudinally of said axial line, one of said end walls

being provided with a diametrical sheet-withdrawal slot extending entirely thereacross and wide enough for insertion of a human finger therethrough for frictional face contact with the innermost one of a pack of sheets so confined in the chamber to withdraw the contacted sheet through said slot, said slot extending only to the juncture of the cylindrical wall with said slotted end wall, and the inner face of said slotted end wall being sloped from said cylindrical wall toward the respective longitudinal edges of said slot, that end wall of the chamber which is opposite said slotted end wall being detachably held to the cylindrical wall and carrying a bar which extends longitudinally of the chamber in contact with the cylindrical wall of the chamber and projects part way across the chamber in registry with said slot, the bar being more narrow than the slot at least at that end of the bar which is nearer the slot.

7. A paper sheet dispenser as defined in claim 1, wherein said housing includes a removable end wall for the cylindrical chamber and a detachable fastening means for holding said wall in place, and wherein said pack locating means is rigidly held to said removable end wall and is detachable therewith from the remainder of said housing.

8. A paper sheet dispenser which, to confine a pack of disconnected and superimposed paper sheets and to provide for manual withdrawal of sheets edgewise thereof one at a time from the confined pack, comprises a housing having two end walls and a cylindrical longitudinal wall connected to confine a pack of disconnected and superimposed paper sheets with the pack held bowed by said cylindrical wall and located between said end walls, said cylindrical wall and one of said end walls being constructed to block withdrawal of sheets therethrough from the confined pack, the other end wall having therein and extending entirely thereacross diametrically of the cylindrical wall a sheet withdrawal slot both ends of which are located at and extend along said cylindrical wall, said slot being sufficiently wide for insertion and withdrawal therethrough of a human finger to withdraw sheets edgewise one at a time through said slot from the concave face of the bowed pack, and said housing having means therein coactive with the sheets of a pack confined in the housing to constrict for passage through said slot the leading end portion of each bowed sheet as the sheet is withdrawn from the pack.
